CAM PIN MECHANISM

Carleton G. Umsted, Northport, and Daniel De Luca, Brooklyn, N. Y., assignors to The Sperry Corporation, a corporation of Delaware

Application July 28, 1945, Serial No. 607,530

2 Claims. (Cl. 74—89)

1

This invention relates to a cam pin mechanism of the kind used in computers for gun fire control.

An object of the invention is to provide a cam lift pin which will operate more efficiently and with less friction than former devices of the kind.

Wear tends to develop flat spots in the ball-shaped end of lift pins commonly used with three dimension cams causing considerable friction between the cam surface and the lift pin, especially when steep slopes on the cam are being traversed, and this results eventually in scoring of the cam surface and binding of the lift pin in its guides. In order to overcome these difficulties the present invention provides a cam pin having a novel ball point which actually rolls over the surface of the cam instead of sliding thereon.

Another feature of the invention is the provision of a cam pin incorporating novel multiplying arrangement.

A further feature of the invention is the provision of a cam pin having a novel mechanism for lifting the cam pin clear of the cam.

The invention in another of its aspects relates to novel features of the instrumentalities described herein for achieving the principal objects of the invention and to novel principles employed in those instrumentalities, whether or not these features and principles are used for the said principal objects or in the said field.

A further object of the invention is to provide improved apparatus and instrumentalities embodying novel features and principles, adapted for use in realizing the above objects and also adapted for use in other fields.

Other features of the invention will appear in the following description given with the aid of the accompanying drawings, of which

Fig. 1 shows a cam pin and associated mechanism in elevation and partly in section;

Fig. 2 is a view in vertical section taken through 2—2 of Fig. 1;

Fig. 3 is a top plan view of an assembly of cam pins partly in section, showing the mechanism by which a plurality of cam pins may be elevated and retained in elevated position clear of the cams to permit changing of the cams; and

Fig. 4 is an enlarged view, partly in section, giving details of a rolling ball arrangement for the end of a cam pin.

The cam pin and associated mechanism as shown in Fig. 1 are preferably supported in a subassembly frame which is attached to the main

2

frame of a computing device for a gun director or the like.

Relative movement of cam 10 and cam pin 11 causes the vertical movement of the latter in bearings 12 and 13 in subassembly frame 14.

The cam pin has an arm 15 pinned thereto provided with an opening through which a guide pin 16 extends. A spring 17 disposed on the guide pin between arm 15 and the framework holds the end of the cam pin in contact with the cam. The upper end of the guide pin is supported for sliding movement in the frame while the lower end is threaded into a nut 18 which turns in bearing 19 in the frame. The nut is retained in the bearing by a shoulder formed thereon and by a threaded ring 20 screwed on a threaded portion of the nut underneath bearing 19. A worm wheel 21 on the upper part of the nut is in mesh with a helical gear 22, Fig. 4, on shaft 23. The shaft is arranged to be turned manually by means not shown, to elevate and lower the cam pin to permit changing of the cam. For this purpose, guide pin 16 has a collar 25 pinned thereto underneath arm 15 disposed normally out of contact with the arm. A screw 26 held by the frame 14 projects into a longitudinal slot 27 milled in the upper part of pin 16 to prevent the pin from turning. To elevate the lift pin, shaft 23 is turned to rotate nut 18 in such direction as to bring collar 25 into engagement with the underside of arm 15, when continued turning of the shaft will cause arm 15 to slide upwards on pin 16 to elevate the lift pin as desired against the pressure of spring 17.

Any suitable pick-off may be operated by the cam pin mechanism thus far described. In the present embodiment of the invention, the cam pin is shown as actuating an output through a novel, simplified, multiplying arrangement.

Adjustably secured between nuts 30 and 31 disposed on a threaded portion of the cam pin is an arm 32 carrying a grooved guide wheel 33 riding on a track 34 fastened to the frame.

A block 35 formed with grooves 36 and 37, Fig. 2, is supported for transverse sliding movement by guides 38 and 39 secured across a central opening in arm 32, the guides entering the grooves 36 and 37, respectively.

Referring to Fig. 2, block 35 carries a pin 40 on which turn rollers 41 and 42 on opposite sides of the block. Roller 42 is disposed between arms 43 and 44 depending from a rack 45 in mesh with

gear 46 on output shaft 47. The rack and the depending arms are assembled as shown in Fig. 2, by being attached to opposite sides of a plate 49, the assembly being supported by grooved rollers 50 attached to rack 45 which ride on a track 51 fastened by screws 52 to the frame, and by a similar pair of rollers 55 riding on track 56 secured by screw 54 to the frame. From the foregoing it will be understood that any transverse movement of block 35 in its guides will 10 actuate output shaft 47.

Roller 41 rides in a slot 57 formed in a link 58 pivoted on a pivot 59 supported in fixed position by the frame. The lower part of the link is formed into a pair of arms 60 and 61 between which is disposed a roller 62 pivoted to a lead nut 63 which turns on a lead screw 64 supported by the frame. A handwheel 65 provided with a suitable scale and index (not shown) is used to turn the lead screw to translate the lead nut and thus vary the inclination of the link 58.

The multiplier arrangement operates as follows. Assuming that pivot 62 is positioned to the right of a perpendicular dropped from fixed pivot 59, to the lead screw, or more accurately, to the locus of pivot 62, then if the cam pin is actuated by the cam, for example, in an upward direction from the position where it is shown in Fig. 1, block 35 will be carried upward by cam pin arm 32, but since roller 41 carried thereby is guided in a slanting direction by slot 57 in link 58, the block will be translated toward the left of the drawing as it moves upward. Roller 42 carried by block 35 will effect a corresponding movement of rack 45 toward the left causing gear 46 to rotate shaft 47 in a clockwise direction. When pin 11 moves downward, the direction of these movements are reversed.

The multiplier operates on the well known principle of the proportionality of corresponding parts of two similar triangles. In the first triangle, one side is the fixed distance of a perpendicular from fixed pivot 59 to the lead screw. The base of the triangle is the distance from the center of pivot 62 to the perpendicular which may be varied by adjusting the lead screw. The hypotenuse is formed by link 58 and changes with the adjustment of pivot 62 which is disposed on the lead nut.

The second triangle is similar to the first and is inverted with respect thereto. One side of the second triangle is a projection of the corresponding side of the first, that is, a line perpendicular to the lead screw extending through fixed pivot 59. The hypotenuse is defined by the position of roller 41 in slot 57 which depends on the angular position at which link 61 is set and the displacement of lift pin 11. The magnitude of the lift pin displacement determines the length of the first mentioned side of the second triangle.

Displacement of the lead nut and pivot 62 away from a zero position, where pivot 62 is directly below fixed pivot 59, determines the extent of the displacement of rack 45 and output shaft 47 for given displacements of the lift pin. The displacement of rack 45 and also of output shaft 47 is proportional to the position of pivot 62 since both are in accordance with the length of the bases of two similar triangles.

With former cam pins, the design of cams was restricted by friction between the cam surface and cam pin which increases with the steepness of the cam slope. The present invention provides a novel ball end for a cam pin which greatly reduces friction between the pin and cam, lessening

ing generally the frictional load on the cam and permitting the traversing of steeper cam slopes.

The cam pin of the present invention, Figs. 1 and 4, is provided with a ball-shaped end 68 from which a spindle 69 projects. The spindle turns in ball bearing assemblies 70 and 71 separated by a spacer 72. The ball bearing assemblies and spacer are retained in a recess formed in a shell 73 by slightly peening the edge of the latter over the lower bearing assembly. A snap washer 74 in a groove in spindle 69 holds the latter in position. Shell 73 has a shank 75 secured thereto, the shank fitting into a complementary recess 77 in lift pin 11 where it is retained in place by a pin 76, Fig. 1.

The lift pin 11 is shown as having replaceable bushings 78 and 79 which ride in bearings 12 and 13 respectively. The lower bearing 12 is shown as a ball bearing assembly which is held in position by a plate 80 secured to frame 14 by screws 81, only one of the latter being shown in the drawing.

Since the point of contact of a cam pin and the surface of the cam is generally more or less offset from the axis of the cam pin, the ball-ended pin of the present invention will roll rather than drag over the cam surface and the reduction in friction is quite evident at the steeper cam slopes where the point of contact is noticeably offset from the axis of the lift pin.

A different set of ballistic cams is required in a gun director for each kind of projectile. In certain directors, ballistic cams are arranged in units of three in tandem. Formerly, when changing the cams, it was necessary to block up the cam pins individually clear of the cams. This method was found to be undesirably slow, especially when done in the field, and occasionally a cam pin would slip from the blocks damaging the pin or denting the cam. The present invention provides an arrangement by which a plurality of cam pins may be positively raised and lowered simultaneously. In Fig. 3 a top view of an assembly of cam pins according to Fig. 1 is shown. Horizontal shaft 23 which is turned manually by means not shown, carries individual helical gears 22 for turning gears 21 for the purpose of elevating the respective guide pins 16 of a plurality of cam pins, two cam pins being shown in the drawing. Shaft 23 as shown in Fig. 3 may be regarded herein as a continuous shaft though actually composed of a number of short sections, the short sections being coupled between the respective cam pins by a suitable coupling device 85 which may be of the Oldham type, to aid in assembling the mechanism. It will be understood that the cam pins normally rest on the associated cams as shown in Fig. 1, the mechanism actuated by shaft 23 for elevating or lowering the cam pins being used only when the device is being serviced.

Since many changes could be made in the above construction and many apparently widely different embodiments of this invention could be made without departing from the scope thereof as set forth in the appended claims, it is intended that all matter contained in the above description or shown in the accompanying drawings shall be interpreted as illustrative and not in a limiting sense.

What is claimed is:

1. A cam pin assembly comprising a cam pin, an arm attached thereto having a hole formed therein, a guide pin extending through the hole in the arm, means for moving the guide pin at

will parallel to the axis of the cam pin, and means normally out of contact with the arm actuated by the movement of the guide pin for engaging and moving the arm to disengage the cam pin from the surface of a cam.

2. A cam pin assembly comprising a cam pin, an arm attached thereto having an opening formed therein, a pin supported for movement in translation but restrained from rotation extending through the opening, a compression spring disposed on the latter pin adapted to engage one side of the arm and hold the cam pin against a cam surface, a threaded portion formed near one end of the last-mentioned pin, a collar secured to the pin on the opposite side of the arm normally out of contact with the arm, a gear provided with internal threads disposed on the threaded portion of the pin, a manually operated shaft for turning the gear to effect translation of the pin for the purpose of bringing the collar into engagement with the arm and moving the arm to disengage the cam pin from the cam surface.
